METHOD OF AND MEANS FOR MAKING
HAT BODIES

George T. Birdsall, Bethel, Conn.

Application June 21, 1950, Serial No. 169,477

28 Claims. (Cl. 223—7)

1

This invention relates to methods and machines for making felt hat bodies.

An object of the invention is to provide an improved method of making a felt hat body, which is extremely simple to carry out and does not require a high degree of skill on the part of the operator.

Another object of the invention is to provide an improved method of making hat bodies according to the foregoing, which produces work of high, uniform quality.

In accomplishing these objects there is provided, in accordance with the invention, a novel method involving the steps of disposing and supporting a predetermined amount of fur merely in a substantially flat layer, preferably horizontal, agitating or working said fur and simultaneously applying hot water to the fur whereby it is compacted and loosely felted into a flat pad. Thereafter, opposite pressures are applied respectively to outer and center portions of said pad and it is agitated or worked and also further subjected to hot water. Preferably the pressures are intermittent, as distinguished from steady, and said pressures when properly applied, together with the agitation and action of the hot water, produce the well-known crown shape to the center portion of the pad, thus forming a hat body.

Preferably the hot water is applied to the underside of the pad and a suction created at the top side, causing the water to be continually sucked upward through the pad, and withdrawing the water vapors.

A further object of the invention is to provide an improved apparatus of simple and reliable construction, for carrying out the above methods of the invention.

Yet another object of the invention is to provide an improved apparatus as set forth, which is to a large extent automatic in its operation whereby a minimum amount of labor is required.

A still further object of the invention is to provide an apparatus in accordance with the foregoing, which has a high productive capacity.

In accomplishing the foregoing objects relating to the apparatus of the invention, I provide a plurality of fur-processing units arranged side by side, and a traveling fur-supply unit adapted to cooperate individually and sequentially with the processing units to supply fur thereto in substantially flat layers of predetermined thickness and weight. I further provide automatic control means whereby the fur-supply unit, after supplying fur to one processing unit, is automatic-

2

cally made to travel to the next to supply fur thereto, and then to the next and so on until all of the processing units have been supplied. After the supply unit has left the first processing unit and is supplying fur to the subsequent units, the first processing unit is working and felting the fur into a completed hat body, and the same is true of the other processing units.

Preferably each processing unit comprises a felting stand, a crown-forming stand and a discharge stand or bench, arranged in a row in the order named, and further comprises three overhead hoods mounting perforated fur-engageable members, the hoods being also arranged in a row and rigidly connected together, and having the same spacing as the stands. The overhead hoods are mounted for four-directional simultaneous movement, and may be made to descend and simultaneously overlie the felting and crown-forming stands and the supply unit when the latter is at the processing unit, or to overlie the three stands of the processing unit. That is, the hoods have two different, lowered positions one of which includes the supply bin and the other of which excludes the bin. When the bin is included, it supplies fur to one of the overhead hoods while the other hoods are picking up processed and formed felt pads or blanks. When the bin is excluded, the hoods are active in the processing of the fur into the pads.

The movements of the hoods are automatically controlled, as is also the operation of agitating means and means for supplying hot water to the fur, located at the felting and crown-forming stands. By this organization the aforementioned method of the invention may be automatically, quickly and economically carried out.

Other features and advantages will hereinafter appear.

40 In the accompanying drawings:

Figure 1 is an elevational view of the improved hat-making apparatus of the invention, drawn to a greatly reduced scale, showing six separate but identical fur-processing units and one traveling fur-supply unit for servicing the processing units.

Fig. 2 is a vertical sectional view of one of the fur-processing units and of the fur-supply unit shown in Fig. 1, taken on the line 2—2 of this figure, the supply unit being shown adjacent the first processing unit, and the scale being slightly enlarged over that of Fig. 1.

Fig. 3 is a fragmentary elevational view of the processing unit shown in Fig. 2, looking in the direction of the arrows 3—3 of this figure.

Fig. 4 is a plan view of one fur-processing unit with the fur-supply unit adjacent it; and

Fig. 5 is a schematic diagram of the control mechanism of the apparatus.

Referring to Figs. 1 and 2, the improved hat-making apparatus of this invention comprises a plurality of fur-processing units 10 through 15 arranged in spaced, side-by-side relation, and a single fur-supply unit 16 for consecutively servicing or supplying each of the aforesaid processing units. The processing units 10 through 15 are disposed along a track 17 over which the fur-supply unit 16 travels; for this purpose it is provided with wheels 18.

Motivation of the supply unit 16 is accomplished by a reversible motor 19 driving, through a gear reduction 20, a chain 21 extending along and below the track 17, said chain having an upstanding coupling member or link 22 extending through a slot 23 in the floor 24 of the building structure which houses the apparatus. The link 22 is connected to the underside of the fur-supply unit 16 as shown in Fig. 1, thereby providing a driving connection between the chain 21 and unit. The transmission between the motor 19 and the chain 21 includes a clutch 25, Fig. 5, actuated by a lever 26.

The fur-supply unit 16 includes a fur storage bin 27, having an inlet opening 28 in its top, which is normally closed by doors 29. The storage bin 27 is connected with a supply or transfer bin 30, which has in its top a circular discharge opening 31, and has pairs of semicircular shutters 32 and 33 adapted to close said discharge opening independently of each other.

The shutters 32 are carried by pivoted arms 34 connected through rods 34a with operating arms 35, the latter being connected by links 36 with a piston 37 carried in a cylinder 38. The shutters 33 are carried by pivoted arms 39 connected by means of rods 39a with operating arms 40 which are in turn actuated by links 41 connected to a piston 42 in a cylinder 43. As shown in Fig. 2, the shutters 32 are disposed in a horizontal plane located above the horizontal plane of the shutters 33.

Fur which is in the supply bin 30 is continually agitated by a fan 44 driven by a motor 45 mounted on the exterior of the bin. Transfer of fur from the storage bin 27 to the supply bin 30 is effected through an opening 46 in the common wall 47 between the two bins, the opening 46 being normally closed except when fur is being transferred. Any suitable closure for the opening 46 may be provided. It is preferable that the supply bin 30 contain at all times a predetermined fixed amount of fur except when it is in process of transferring fur to a processing unit, and such amount may be controlled by any suitable means (not shown), details of which are not included in the present invention. It is intended, however, that for each quantity of fur which is discharged and transferred from the transfer bin 30 through the discharge opening 31 thereof to a processing unit, an equal quantity will be later deposited in said bin from the storage bin 27 through the transfer opening 46 in the wall 47 between the bins.

The processing units 10 through 15 are identical to each other, each comprising a platform 48 having a felting stand or station 49, a forming stand or station 50 and a discharge stand or station 51. The stands 49, 50 and 51 are located in a row on the platform 48, and are spaced apart equal distances, and the stand 49 is spaced from

the discharge opening 31 of the transfer bin 30, when the latter is alongside of the station 49, the same distance as the spacing between the stands.

The felting stand 49, which is the place where the fur is initially worked, comprises a perforated, flat plate 52 set across the top of a basin 53 in which a circular spray pipe 54 having orifices 55 is mounted. The orifices 55 are located to direct fluid such as hot water from the spray pipe 54 upward against the underside of the plate 52. At its bottom the basin 53 has a drain pipe 56. Hot water under pressure is supplied to the spray pipe 54 by a supply pipe 57 controlled by a valve 57a.

The perforated plate 52 is carried in a circular frame 58 and is reciprocated edgewise, that is, in its own plane by means of a motor 59 having an eccentric 60 engaged by a fork 61 of a pivoted lever 62 which makes a driving connection with the frame 58 as clearly shown in Fig. 2. The frame 58 is recessed into the platform 48 and movably carried in said recess to permit such reciprocation, as will be well understood.

The forming stand 50 comprises a perforated plate 63 having a large center opening 64 to admit a perforated crown-shaped forming member 65 mounted in a basin 66 for vertical reciprocative movement. The member 65 is carried by a plunger 67 connected with a piston 68 mounted inside of a cylinder 69, the latter being mounted on a cross member or strut 70 secured to the side walls of the basin 66. The forming member 65 may thus be moved upwardly through the opening 64 in the plate 63, to project a substantial distance above the plate, and during such upward or advancing movement it may be reciprocated, as will be later brought out in detail. A circular spray pipe 71 is also mounted in the basin 66 to encircle the member 65, the spray pipe having orifices 72 for directing hot water upwardly against the member 65 and against the underside of the perforated plate 63. The spray pipe 71 is supplied with hot water under pressure from a supply pipe 73 having a control valve 74.

The perforated plate 63 is carried in a frame 75 which is recessed in the platform 48, the frame being horizontally movable between limits and being reciprocated by a pivoted lever 76 having a fork 77 engaged by an eccentric 78 driven from a motor 79. The basin 66 has a drain pipe 80 at its bottom, connected with the drain pipe 56. The discharge bench or stand 51 comprises merely a flat table surface 81 on the platform 48.

Each fur-processing unit also comprises a plurality of hoods 82, 83 and 84 respectively connected with telescopic two-part risers 85, 86 and 87 joined at their top ends with a manifold pipe 88. The risers 85, 86 and 87 have outer parts or sleeves 89, 90 and 91 to the lower portions of which the hoods are fixedly secured, said sleeves being mounted by studs 92 and cushion spring 92a on a horizontal frame 93 sliding on vertical guide rods 94 anchored at their top ends to a carriage 95. The carriage 95 has wheels 96 riding on overhead tracks 97 secured by hangers 98 to the ceiling 99 of the building structure which houses the apparatus. The tracks 97 extend over the platform 48 and enable the hoods 82, 83 and 84 to be brought into registration respectively either with the felting stand 49, forming stand 50 and discharge bench 51, or with the discharge opening 31 of the transfer bin 30, the felting stand 49 and the forming stand 50. Registration of the hood 82 with the discharge opening 31

of the transfer bin 30 is indicated in Fig. 2 by the broken outlines 100 and 101.

The frame 93 and the hoods 82, 83 and 84 carried thereby may be moved vertically from the position shown in Fig. 2 downward to a position wherein the hoods cover or overlie the stands 49, 50 and 51. These lowered positions of the hoods are indicated by broken outlines in Fig. 2. When the carriage is shifted to the left from the position shown in Fig. 2, so as to bring the hood 82 into registration with the discharge opening 31 of the transfer bin 30 (indicated by the broken outline 100) it may be again lowered, and this lowered position wherein the hood is directly on top of the bin 30 is indicated by a second broken outline. For such position the hoods 83 and 84 will be respectively overlying the felting stand 49 and the forming stand 50.

Movement of the carriage 95 along the tracks 97 is hydraulically controlled, being effected by a cylinder 102 mounted on the carriage, containing a piston 103 joined to a piston rod 104 which is fixedly attached to one of the hangers 98 for the tracks 97.

The manifold 88 of the hoods is carried by straps 105 from which depend piston rods 106 having pistons 107 contained in cylinders 108 which are at their upper ends secured to the horizontal frame 93. Vertical movement of the frame 93 and hoods 82, 83 and 84, together with the sleeves 89, 90 and 91 may thus be hydraulically controlled by means of the pistons 107 and cylinders 108.

The hood 82 forms part of a fur-collecting head, and for this purpose the bottom of the hood is provided with a perforated, flat plate or support 109, extending across its mouth. The bottom of the hood 83 also has a perforated plate 110, in the form of a hat mold, and the bottom of the hood 84 has a hollow perforated transfer member 111 similar to the hat mold 110.

The upper or inner portions of the risers 85, 86 and 87 are provided with butterfly valves 112 actuated by solenoids 113, 113a and 113b whereby energization of any of the latter opens the associated valve or valves. Closing of the valves is effected by return springs 114. The right-hand end of the manifold 88 slidably fits in a sleeve 115 carried by a hanger 116, the sleeve 115 being stationary and connected with a vacuum pump (not shown) whereby lower air pressures may be produced in the risers 85, 86 and 87 and the hoods 82, 83 and 84 when the butterfly valves 112 are open.

For effecting automatic controls of the movements of the hood assemblage, limit switches 117 and 118 are mounted on the underside of the horizontal frame 93, for engagement with arms 119 carried by the guide rods 94, such engagement occurring when the frame 93 is in lowered position. Limit switches 120 and 121 are carried by the inner, telescoping part of the riser 86 for engagement by the frame 93 when the latter is in the raised position shown in Fig. 2. Limit switches 122 and 123 are carried by the ceiling surface 99 of the building structure, for engagement with an upstanding arm 124 on the carriage 95 when the latter is respectively in its extreme left and right positions.

The piston 103 and cylinder 102 are controlled by a solenoid-operated valve 125; likewise the pistons 107 and cylinders 108 are controlled by a solenoid-operated valve 126, see Figs. 2 and 5. Referring to the forming table or stand 50, the

piston 68 and cylinder 69 are controlled by a solenoid-operated valve 127.

In accordance with the present invention a novel method is provided for forming hat bodies, said method being conveniently and effectively carried out by the apparatus described above, in conjunction with automatic control means shortly to be described. The improved method will now be described in conjunction with the apparatus set forth above, although it should be understood that the method may be carried out by hand or by apparatus other than that shown and described. The control means mentioned causes the fur-supply unit 16 to automatically service each of the processing units 10 through 15 sequentially. In doing this, the fur supply unit 16 travels back and forth along the track 17 provided for it, and dwells at each of the processing units 10 through 15 for a predetermined length of time.

When the supply unit 16 is at one of the processing units, the hoods 82, 83 and 84 will be lowered respectively over the transfer bin 30, the felting stand 49 and the forming stand 50, and will dwell in said position for a predetermined length of time during which the shutters 32 and 33 are actuated to enable a predetermined amount of fur to be deposited on the underside of the flat support 109 of the hood 82. In effecting such deposit of fur, the lowered air pressure in the manifold 88 is utilized, by opening of the associated butterfly valve 112. The hoods 82, 83 and 84 are then raised and shifted to the right, to the position shown in Fig. 2, and again lowered. A mat or pad 128 of fur, which has been deposited on and retained by the support 109 will therefore be disposed between the support 109 and the perforated plate 52 of the felting stand 49.

The hoods 82, 83 and 84 will dwell for an interval of time in their lowered positions respectively over the stands 49, 50 and 51, during which interval the pad 128 will be felted and compacted by agitation of the plate 52 and application of hot water to the fur, from the orifices 55. The felted and compacted pad 128 will be allowed to remain on the plate 52 (effected by closure of the valve 112 in the riser 85, which shuts off the vacuum from the hood 82) while the hoods 82, 83 and 84 are raised and again shifted to the left and thereafter lowered. The pad 128 on the stand 49 will now be picked up by the suction of the hood 83, and when the hoods are again raised, shifted to the right and lowered, the pad 128 will be disposed under the hat mold 110 and will be subjected to the action of the forming member 65 and further felted, to produce a crown in the pad. This is effected by intermittent raising movements of the member 65 plus the application of hot water from the orifices 72 and agitation of the plate 63.

The crowned pad is allowed to remain on the plate 63 of the forming stand 50, by shutting off suction from the hood 83, and the hoods 82, 83 and 84 are again raised, shifted to the left, and lowered whereupon the crowned pad will be picked up by the suction of the hood 84. While this is occurring, the hood 83 will be picking up another flat felted pad from the stand 49 and the hood 82 will be having fur deposited on the underside of the support 109. During the next operation of raising the hoods, shifting them to the right and lowering them, the crowned pad carried by the hood 84 will be deposited on the discharge bench 81, from which it may be readily removed by hand.

The apparatus is so arranged that after the processing unit 15 has been supplied with a quantity of fur under the hood 82, the fur-supply unit 16 will move to the next processing unit 14 to supply this unit with fur; meanwhile the unit 15 will be processing the fur which has been supplied to it, in the manner briefly described above. From the unit 14, the fur-supply unit 16 moves to the processing unit 13, then to the unit 12, the unit 11 and the unit 10, after which it is returned to the unit 15 to provide a second quantity of fur. Thus the processing units 10 through 15 are supplied in rotation, and the processing of the fur is preferably timed with the number of processing units employed and the time required to transfer the fur from the supply bin to the units, so as to most economically utilize the equipment.

The automatic control means of the present hat-making apparatus is shown diagrammatically in Fig. 5. In this figure at the left, the fur-supply unit 16 is indicated by a broken rectangular outline, inside of which the pistons 37, 42 and cylinders 38, 43 are depicted. These pistons and cylinders are controlled respectively by valves 129 and 130 actuated by solenoids 131, 132, 133 and 134. A limit switch 135 is arranged to be closed whenever the piston 37 is in its rightmost position as shown, and to be open whenever the piston is shifted from said position to the left. A S. P. D. T. limit switch 136 is provided on the top of the transfer bin 30, Figs. 2, 4 and 5, to be actuated by an arm 137 on the hood 82 when the latter is lowered over the supply bin 30, and a switch 136a is mounted on the bin 30, and arranged to be momentarily closed by the hood 82 whenever it ascends from the bin. Also, a switch 138, Figs. 4 and 5, is mounted on the top of the bin 30, to be actuated by a lug 139 on the platform 48 when the supply unit 16 arrives at the proper position adjacent a processing unit.

The fur-supply unit 16 also carries a pair of current pickup shoes 140 and 141 adapted to engage rails 142 and 143 respectively, extending for the full length of the track 17. The unit 16 in addition mounts three electric brushes 144, 145 and 146 adapted to engage cooperable contacts 147, 148 and 149 respectively, said contacts being provided on each processing unit.

Each one of the processing units 10 through 15 has a switch 150 mounted on the platform 48, actuated by a projection 151 on the side of the supply unit 16 when the latter is at the processing unit.

In the upper part of Fig. 5 the piston 103 and cylinder 102 are diagrammatically indicated, also the solenoid valve 125, which is actuated by solenoids 132 and 133. The limit switches 122 and 123 for the carriage 95 are also indicated in the upper portion of Fig. 5, and the solenoid-operated butterfly valves 112. Limit switches 117, 118, 120 and 121 associated with lowering and raising the horizontal frame 93 which carries the hoods 82, 83 and 84, are shown associated with the pistons 107 and cylinders 108. The lowering and raising of the pistons 107 is controlled by a solenoid valve 154 actuated by solenoids 155 and 156. Below the solenoid valve 154 the valve 127 is pictured, operated by solenoids 157 and 158. Fluid for actuating the pistons and cylinders of the processing units is supplied under pressure by a pump 159 and tank 160. To provide pulsations in the fluid supply to the cylinder 69, to intermittently raise the forming member 65 at the forming stand 50, a cylinder 161 is connected in the supply line

162 of the cylinder 69, and a piston 163 in the cylinder 161 is reciprocated by an eccentric 164 driven by an electric motor 165. It should be noted that the piston 163 and cylinder 161 enable the member 65 to have retrograde movements, which are of lesser magnitude than its advancing movements.

Considering the felting stand 49 and forming stand 50, the valves 74 and 57a controlling the supply of hot water thereto are controlled by solenoids 166 and 167, energized through manually operated switches 168 and 169. Both said solenoids are connected to a common supply wire 170 which also connects with the motors 59 and 79 for reciprocating the plates 52 and 63 respectively.

Control of the components set forth above is mainly effected by a drum 171, shown diagrammatically in Fig. 5 as a rectangular development 20 of the drum surface, said drum being driven by a motor 172 and having contact segments 173 through 187 respectively, cooperable with brushes 188 through 202. The contact segment 173 is a supply segment for connection with the line, and 25 is connected to all of the other contact segments, as shown. The various segments on the drum have different lengths and positions as indicated, and for the starting position shown only the segment 173 is in contact with the brush 188. 30 Advancing movement of the drum is the same as traversing the segments from right to left by the brushes.

The electrical connections between the various components of the control mechanism are as follows: Current is supplied by two lines 203 and 204. Line 203 is connected by a wire 205 with the motor 19, through a reversing and stop-start switch 206, which is connected by a wire 207 with the line 204. A wire 208 connects the line 203 with a solenoid 209 which is arranged to actuate the clutch lever 26 against the action of a return spring 210. The solenoid 209 is connected by a wire 211 with the current conducting rail 143, and the associated rail 142 is connected by a wire 212 with the line 204. The current-collecting shoes 140 and 141 are connected by wires 213 and 214 respectively to a contact 215 and cooperable contact blade 216 of the switch 136a. Also, the collecting shoes 140 and 141 are connected to the terminals of the switch 138. The blade 217 of the switch 136 is connected by a wire 218 with the solenoids 133 and 134, and with the brush 145. The remaining end of the solenoid 134 is connected by a wire 219 with the brush 146, and the remaining brush 144 is connected by a wire 220 with ends of the solenoids 131 and 132. The wire 220 also connects with one terminal of the limit switch 135 the other terminal of which is connected by a wire 221 with the remaining end of the solenoid 133. The remaining end of the solenoid 132 is connected by a wire 222 to one contact of the limit switch 136, the opposite contact of said switch being connected by a wire 223 to the remaining end of the solenoid 131.

The supply unit 16 has a hydraulic system comprising a tank 224, motor and pump unit 225 and fluid supply line 226 leading from the pump unit to branches 227 and 228 which respectively connect with the valves 129 and 130. The valves 129 and 130 have discharge lines 229 and 230 emptying into the tank 224. Hydraulic lines 231 and 232 connect the valve 130 with the cylinder 43, and lines 233 and 234 connect the cylinder 38 with the valve 129.

The valves 129 and 130 have spools 235, 236,

237 and 238 which are actuated by the solenoids 131 through 134 in a manner well understood, to selectively connect the hydraulic lines of the hydraulic system, as will be described below in more detail.

The switch 138 is normally closed, being open only whenever the supply unit 16 is at a processing unit. Also, the limit switch 136 is normally in the position shown, and is actuated to its other position whenever the hood 82 descends over the transfer bin 30. The limit switch 135 is normally open, and is closed whenever the piston 37 is in the rightmost position shown in Fig. 5.

The main electric supply line 204 is also connected by a wire 239 with the motor 172, the latter having its other terminal connected by a wire 240 with the switch 150. From the switch 150 a wire 241 connects with the supply line 203. The switch 150 is normally open, and is closed whenever the supply unit 16 is at the processing unit.

The wire 240 is connected by a wire 242 with the brush 202, and this constitutes a holding circuit for the motor 172 which operates to carry 25 the drum 171 through a complete revolution after the drum has been initially started by closing of the switch 150. In other words, after the supply unit 16 leaves the processing unit, thus opening the switch 150, the drum 171 will continue to rotate and complete its revolution because of the holding circuit established between the drum segment 187 and the brush 202. Upon the segment 187 leaving the brush 202, the drum 171 will come to a halt and will not be again started until the supply unit 16 again returns to the processing unit. Such return, however, will automatically again start up the drum and cause it to carry through another cycle of operations.

Connections to the brushes 189 through 201 of the drum, and the associated connections are as follows: The brush 189 is connected by a wire 243 to one contact 244 of the limit switch 123. The brush 190 is connected by a wire 245 with one end of the solenoid 113b and with a contact 246 of the limit switch 121. The brush 191 is connected by a wire 247 with one end of the solenoid 113a and with another contact 248 of the limit switch 121. The brush 192 is connected by a wire 249 with one end of the solenoid 113 and with a third contact 250 of the limit switch 121. The brush 193 is connected by a wire 251 with a contact 252 of the limit switch 118 and with a contact 253 of the limit switch 122. The brush 194 is connected by a wire 254 with all three blade contacts of the switch 121. The brush 195 is connected by a wire 255 to one terminal of the switch 169 and of the motor 79 which reciprocates the perforated plate 63 of the forming stand 50. The brush 196 is connected by a wire 256 to one terminal of the switch 168 and with the motor 59 which reciprocates the perforated plate 52 at the felting stand 49. The brush 197 is connected by a wire 257 to one end of the solenoid 155. The brush 198 is connected by a wire 258 to one terminal of the limit switch 117, and the brush 199 is connected by a wire 259 to one end of the solenoid 157. The brush 200 is connected by a wire 260 to one end of the solenoid 158, and the brush 201 connected by a wire 261 to the contact 149.

The limit switch 123 has a second contact 262 which is connected by a wire 263 with a second contact 264 of the limit switch 122 and with one end of the solenoid 156. The other end of the

solenoid 156 is connected by a wire 264 with one end of the solenoid 153, the other end of which is connected by a wire 265 with a second contact 266 of the limit switch 118. The three remaining ends of the solenoids 113, 113a and 113b are connected together by a wire 267 which connects with one terminal of the limit switch 120 and also with one end of the solenoid 152. The other end of the solenoid 152 is connected by a wire 268 with the remaining terminal of the limit switch 117.

The remaining terminals of the motors 59 and 79, and of the solenoids 166 and 169 are all connected together by a wire 269 which connects 15 with the remaining end of the solenoid 153. The remaining ends of the solenoids 155 and 157 are also connected to the wire 267, which is also joined to the wire 212. A wire 270 connects the wire 267 with the contact 148, and the wire 270 also connects with one terminal of the motor 165 20 the other terminal of which is connected by a wire 271 to the wire 255. The contact 147 is connected by a wire 272 to the wire 242.

It will be understood that the limit switches 117, 118, 120, 121, 122 and 123 are normally open except when actuated by their respective operators.

The hydraulic control system of the processing unit shown in Fig. 5 includes a tank 213 and a motor and pump unit 214, the latter having a delivery line 275 connected by branches 276, 277 and 278 to the valves 127, 154 and 125 respectively. Fluid supply lines 279 and 280 extend from the valve 125 to the cylinder 192. Fluid supply lines 281 and 282 extend from the valve 154 to the cylinders 108, and fluid supply lines 283 and 162 extend from the valve 127 to the cylinder 69.

The valves 125, 154 and 127 have, respectively, discharge lines 284, 285 and 286 connecting with a main discharge pipe 287 which returns fluid to the tank 213.

Operation of the apparatus described above is as follows: Considering Figs. 1 and 4, the storage bin 27 of the fur-supply unit 16 is first filled with fur, by opening the door 29. A predetermined quantity of fur is then transferred from the bin 27 to the bin 30 through the opening 46 in the partition wall 47 separating the bins. The opening 46 is closed and the blower 44, 45 set into operation, causing the fur in the supply bin 30 to be continually agitated and to be uniformly dispersed in the bin. During this procedure the upper shutters 32 of the bin 30 are closed, and the lower shutters are open.

Referring to Fig. 5, assume that the lines 203 and 204 are supplied with current. The operator now starts the pump and motor units 214 of the processing units 10 through 15 and closes the switches 168 and 169 of said units. He then closes the switch 206, causing the motor 19 to be energized and driving the supply unit 16 from right to left as viewed in Fig. 1. When the supply unit 16 reaches the processing unit 15 the switch 138 will be opened, the switch 150 closed and the brushes 144, 145 and 146 will engage respectively the contacts 147, 148 and 149. Opening of the switch 138 will result in de-energization of the solenoid 209 enabling the spring 210 to become operative to disconnect the clutch 25. This is the control which positions the fur-supply unit 16 adjacent the processing units, and the supply unit will thus be halted in operative position at the first processing unit 15.

Closing of the switch 150 energizes the drum driving motor 172, causing rotation of the drum

171. Immediately upon the drum 171 starting to turn, the drum segment 172 will engage the brush 193. This will energize the solenoid 153, shifting the valve 125 to the right and causing the carriage 95 to be advanced from right to left. In tracing this circuit, it will be seen that current flows through the line wire 293 and the drum segment 173 to the segment 170, thence through the brush 193 and wire 254, switch 118 and wire 265 to the solenoid 153. The return of the solenoid includes the wires 267 and 212, connecting with the line wire 294.

When the carriage reaches its leftmost position it closes the limit switch 122, energizing the solenoid 156 and shifting the valve 154 to the right. This will cause the frame 93 and the risers and hoods carried thereby to start downward in their leftmost positions. Drum segments 179 and 187 will thereafter shortly come into contact with the brushes 194 and 202. Contact between segment 187 and brush 202 results in a holding circuit being established through the motor 172, as already explained, maintaining the motor energized after the switch 156 has been opened in response to departure of the supply unit 16 from the processing unit 15 at a later time. In consequence of this the drum 171 will be carried through one complete revolution, until segment 187 breaks from brush 202.

Engagement of the segment 179 with the contact 194 brings current to the blade contacts of the limit switch 121 controlling the solenoids 113, 113a and 113b which actuate the butterfly valves 112. These valves are normally closed as shown. Upon further advance of the drum 171 the segment 178 will leave its associated contact 193. Shortly after this occurs, the frame 93 will attain its lowermost and leftmost position, placing the hoods 82, 83 and 84 respectively over the bin 30, felting stand 49 and forming stand 50. This will close the limit switches 120 and 121, the latter causing energization of the solenoids 113, 113a and 113b and opening the butterfly valves 112 whereby suction is established in the hoods 82, 83 and 84. Closing of the switch 120 will connect the electrical return circuit of the control to the motors 59, 79, and to the solenoids 166 and 167, preparatory to these being energized later. Also, the hood 82 when in lowered position will actuate the switch 136 carried on the bin 30, causing contact to be established between the wires 218 and 222 and energizing the solenoid 132 on the supply unit. This will shift the valve 129 to the right, causing the piston 37 to be driven to the left and opening the upper shutters 32 of the bin so that fur will be withdrawn from the latter.

After this occurs, and upon further rotation of the drum 171, the segments 175, 176 and 177 will engage respectively the contacts 190, 191 and 192. Such engagement establishes holding circuits for the solenoids 113, 113a and 113b, maintaining the butterfly valves 112 open. Additional movement of the drum 171 will cause the segment 179 to separate from the contact 194, disconnecting the limit switch 121 from its source of supply. Still further rotation of the drum will cause the segment 184 to be brought into contact with the brush 199, resulting in energization of the solenoid 157. This will shift the valve 127 to the left and will cause hydraulic fluid to enter the top of the cylinder 69, lowering the forming member 65 from the position shown in Fig. 5. As the drum 171 continues to rotate the segment 184 will be disconnected from the contact 199. Meanwhile fur is being collected on the underside of the sup-

port plate 109 of the hood 82, due to the suction in the hood sucking the fur from the supply bin 30, and this will continue while the drum 171 advances further. The drum segment 186 will now be brought in contact with the contact 201, and this will energize the solenoid 134 of the supply unit 16, shifting the valve 130 to the right and causing the lower shutters 33 of the bin to be closed, discontinuing pickup of fur from the bin by the hood 82. The interval between the time that the hood 82 descends on the bin 30 and the time that the segment 186 engages the contact 201 is chosen to enable a predetermined desired amount of fur to be deposited on the underside of the support plate 109. As the drum continues to rotate further the segment 182 will engage the contact 197, and this will cause energization of the solenoid 155, shifting the valve 154 to the left and forcing hydraulic fluid through the line 281 to the tops of the cylinders 108, thus raising the frame 93 and the risers and hoods carried thereby. As the hood 82 rises, the switch 136 will be actuated to connect together the wires 218 and 223, energizing the solenoid 131 and shifting the valve 129 to the left, thereby closing the top shutters 32, and this in turn will result in the bottom shutters opening, due to closing of the switch 135. Also, as the hood 82 rises it will momentarily close the switch 136a, energizing the solenoid 209 and actuating the clutch 25 whereby the fur-supply unit 16 will be caused to leave the processing unit 15. Such departure will be accompanied by closing of the switch 138 which will maintain the solenoid 209 energized until the supply unit 16 reaches the next processing unit. Practically at the same time the drum segment 186 will disengage the associated contact 201, and shortly after this the drum segment 183 will engage the contact 198. Such engagement energizes the limit switch 117, and when the frame 93 reaches its uppermost limit of movement and closes the limit switch 117, this will cause energization of the solenoid 152, shifting the valve 125 back to the left. This in turn will cause the carriage 95 to start retracting to the right. During such retraction continued rotation of the drum 171 will result in the segments 182 and 183 disengaging, in the order named, their respective contacts 197 and 198, and thereafter the drum segment 174 will be brought in engagement with the contact 189. This will energize the limit switch 123, and when said switch is closed by the carriage 95 reaching its rightmost position shown, the solenoid 156 will be energized, shifting the valve 154 to the right and causing hydraulic fluid to enter the lower portions of the cylinders 108 and causing the frame 93 to start a descent. At the termination of such descent, turning of the drum 171 will bring the drum segments 180, 181 and 185 in engagement with their respective contacts 195, 196 and 200. These engagements will cause energization of the agitator motors 59 and 79, and of the solenoids 166 and 167 which actuate the valves 58 and 74. Also energization of the solenoid 158 will be effected, shifting the valve 127 to the right and causing hydraulic fluid to enter the cylinder 69 and slowly raise the forming member 65. Pulsations will be imparted to said fluid by the piston 163 driven by the motor 165, which is energized concurrently with the motor 79 and solenoid 167. The flow of fluid into the cylinder 69 will be controlled by a relief valve (R. V.) inserted in the hydraulic line 162, whereby the member 65 will be raised at a predetermined relatively slow rate. At the same time that this is

happening the drum segment 175 will separate from its associated contact 190, de-energizing the solenoid 113b and closing the associated butterfly valve 112. This will shut off the vacuum from the riser 87 and the hood 84, and will result in the hood dropping the formed hat body which it has picked up from the forming stand 50, on the discharge bench 51.

With the hoods 82, 83 and 84 lowered in rightmost positions, the layer of fur which is carried by the support 109 will be worked, and subjected to hot water and steam at the felting table or stand 49, and will be compacted and felted over an interval of time into a pad having a certain amount of body; also the felted pad which was previously picked up from the stand 49 by the hood 83 will have a crown formed in it by the member 65, since it is subjected to opposing forces on its central and outer portions, and also to hot water and further agitation.

While this is occurring, further rotation of the drum 171 will cause disengagement between the segments 174 and 185 and their associated contacts 189 and 200. After an interval has elapsed which is sufficient to enable the fur at the station 49 to be sufficiently felted, the drum in its rotation will cause the segment 177 to disengage the contact 192, de-energizing the solenoid 113 and resulting in the associated butterfly valve 112 closing. This will shut off the vacuum from the hood 82, and will result in the felted pad at the stand 49 remaining thereon after the hood 82 has been raised from said stand. Also, the drum 171 will separate the segment 181 from the contact 196, de-energizing the agitator motor 59 and the solenoid 166 and closing the valve 57a.

After a further interval has elapsed which is sufficient to enable the member 65 to completely form a crown in the hat body, the drum 171 will by its rotation disengage the segment 176 from the contact 191, de-energizing the solenoid 113a and closing the associated butterfly valve 112. Vacuum will be shut off from the hood 83, thereby enabling the formed hat body to remain on the forming stand 50 when the hood is raised from said table. The drum rotation will also cause disengagement of the segment 180 from the contact 195, de-energizing the motor 79 and the solenoid 167, thereby inactivating the forming stand 50. Upon this occurring, segment 182a on the drum will engage the contact 197, resulting in energization of the solenoid 155, shifting the valve 154 to the left and causing the frame 93 to be raised. Further rotation of the drum 171 will disengage the segment 182a from the contact 197, and thereafter disengage the segment 181 from the contact 202, and this latter will de-energize the drum driving motor 172 and will halt the drum.

The processing unit will thus automatically come to rest after completion of a cycle, and will remain at rest for a short period, until the supply unit 16 again returns.

During the processing of the fur by the unit 15, the unit 16 is supplying fur to the remaining units 10 through 14, and the time of processing is preferably slightly less than the time required for the unit 16 to service the remaining five processing units, so that the time during which any one processing unit is at rest is held to a minimum.

After the supply unit 16 has serviced the processing unit 10 the operator reverses the motor 19 and brings the supply unit back to the start-

ing position shown in Fig. 1, to receive a new supply of fur.

It will be understood that when the hoods 82, 83 and 84 are in their leftmost, lowermost positions wherein fur is deposited on the underside of the support plate 109, the hood 83 will be picking up the felt pad which was previously left on the stand 49 by the hood 82, and the hood 84 will be picking up the formed pad which was previously left on the stand 50 by the hood 83. Also, when the hoods are in their rightmost, lowermost positions the fur which has been deposited on the underside of the support 109 will be felted at the stand 49 at the same time that the felted pad carried by the hood 83 is being formed at the forming stand 50, and the hood 84 will be discharging a formed hat body on the bench 51, which it had previously picked up from the stand 50.

I have thus provided by the present invention an extremely simple and effective method of forming felt hat bodies, and a desirable apparatus for carrying out said method. The method and apparatus are reliable, require a minimum of skill, and produce hat bodies of high uniform quality at a high production rate. Moreover, a minimum of labor is required in operating the apparatus of the invention.

The timing of the various steps in the method may obviously be made to suit specific conditions. I have described herein one complete cycle in the operation of my improved apparatus, with the various components actuated in a particular sequence, for purposes of illustration only.

If desired the water which is used at the felting stand 49 and forming stand 50 may be colored by means of suitable dyes, thereby to impart coloring to the fur during the processing operation thereof. Accordingly, a finished hat body which is deposited on the bench 51 may be either partly or completely colored, depending on the requirements and the amount of coloring matter used in the water. Inasmuch as a suction exists in the hoods 85 and 86, the colored water which is used in the felting operations will be sucked through the fur being felted, thereby permeating the fur and providing for an even coloring of the hat body.

Variations and modifications may be made within the scope of the claims and portions of the improvements may be used without others.

I claim:

1. The method of making a hat body from a substantially flat felt pad, which includes the steps of applying opposing pressures to outer portions of said pad to hold said portions in predetermined relative positions, applying pressure to the center portion of the pad in the direction of one of said opposing pressures to displace said portion laterally with respect to the outer portions and outside of the plane of said outer portions, agitating the pad, and applying heat and moisture to the pad, all simultaneously, for the purpose of forming a crown in the pad.

2. The method of making a hat body from a substantially flat felt pad, which includes the steps of applying opposing pressures to outer portions of said pad to hold said portions in predetermined relative positions, applying intermittently pressure to the center portion of the pad in the direction of one of said opposing pressures to displace said portion laterally with respect to the outer portions and outside of the plane of said outer portions, agitating the pad,

and applying hot water to the pad, all simultaneously, for the purpose of forming a crown in the pad.

3. The method of making a hat body from a substantially flat felt pad, which includes the steps of applying opposing pressures to outer portions of said pad to hold said portions in predetermined relative positions applying pressure to the center portion of the pad in the direction of one of said opposing pressures to displace said portion laterally with respect to the outer portions and outside of the plane of said outer portions, agitating the pad, and applying hot water to the pad, all simultaneously, for the purpose of forming a crown in the pad, and thereafter sucking air through said pad to remove moisture therefrom.

4. The method of making a hat body which includes the steps of disposing a predetermined amount of fur in a substantially flat layer, agitating said fur and simultaneously applying heat and moisture thereto to felt the fur into a compressed substantially flat pad, and thereafter simultaneously agitating the pad, applying opposing pressures to outer portions of said pad to hold said portions in predetermined relative positions, applying pressure to the center portion of the pad in the direction of one of said opposing pressures to displace said portion laterally with respect to the outer portions and outside of the plane of said outer portions, and applying heat and moisture to the pad, to form a crown therein.

5. The method of making a hat body from a substantially flat felt pad, which includes the steps of applying opposing pressures to outer portions of said pad to hold said portions in predetermined relative positions, applying pressure to the center portion of the pad in the direction of one of said opposing pressures to displace said portion laterally with respect to the outer portions and outside of the plane of said outer portions, agitating the pad, and applying hot water to one side of the pad and sucking the water through the pad, all simultaneously, for the purpose of forming a crown in the pad.

6. The method of making a hat body which includes the steps of disposing a predetermined amount of fur in a substantially flat layer, agitating said fur and simultaneously applying heat and moisture to one side of said layer and sucking said moisture through the layer, to felt the fur into a compressed substantially flat pad, and thereafter simultaneously agitating the pad, applying opposing pressures to outer portions of said pad to hold said portions in predetermined relative positions, applying pressure to the center portion of the pad in the direction of one of said opposing pressures to displace said portion laterally with respect to the outer portions and outside of the plane of said outer portions, applying heat and moisture to one side of the pad and sucking said moisture through the pad, to form a crown therein.

7. The method of making a hat body which includes the steps of disposing a predetermined amount of fur in a substantially flat layer, agitating said fur and simultaneously applying hot water thereto to felt the same into a compressed substantially flat pad, and thereafter simultaneously agitating the pad, applying opposing pressures to outer portions of said pad to hold said portions in predetermined relative positions, applying intermittently pressure to the

center portion of the pad in the direction of one of said opposing pressures to displace said portion laterally with respect to the outer portions and outside of the plane of said outer portions, and applying hot water to the pad, to form a crown therein.

8. Apparatus for making hat bodies, comprising a substantially flat support; means for transferring fur from a supply to said support; control means rendering operative the said preceding means for a predetermined period of time, to deposit a predetermined amount of fur on said support; means for felting said fur into a substantially flat pad; means automatically rendering operative said felting means for a predetermined period of time, commencing after halting of said transferring means; means for applying opposing pressures to outer and center portions respectively of said pad; means for further felting said pad; and means automatically rendering operative the two immediately preceding means upon completion of felting of the fur into the flat pad.

9. Apparatus for making hat bodies, comprising a fur supply; means for removing fur from said supply and depositing it in a substantially flat, uniform layer; means rendering operative said preceding means for a predetermined period of time, to deposit a predetermined amount of fur in said layer; means for agitating said layer of fur; means automatically rendering operative said agitating means for a predetermined period of time, commencing after halting of said depositing means; means automatically applying heat and moisture to said fur during the agitating thereof, to felt the fur into a substantially flat pad; means for applying opposite pressures to outer and center portions respectively of said felted pad; means for agitating said felted pad; means for applying heat and moisture to said felted pad; and means automatically rendering operative said three immediately preceding means upon completion of felting of the fur into the flat pad.

10. Apparatus for making hat bodies, comprising a fur supply; means for removing fur from said supply and depositing it in a substantially flat, uniform layer; means rendering operative said preceding means for a predetermined period of time, to deposit a predetermined amount of fur in said layer; means for agitating said layer of fur; means automatically rendering operative said agitating means for a predetermined period of time, commencing after halting of said depositing means; means automatically applying heat and moisture to said fur during the agitating thereof, to felt the fur into a substantially flat pad; means for transporting said felted pad to another location; means automatically rendering said transporting means operative after completion of felting of the fur into the pad; means for applying heat and moisture to said felted pad at said other location; means for applying opposite pressures to outer and center portions respectively of said pad at said other location; and means automatically rendering operative said two immediately preceding means after transportation of the pad to said other location.

11. Apparatus for making hat bodies, comprising a fur supply; means for removing fur from said supply and depositing it in a substantially flat, uniform layer; means rendering operative said preceding means for a predetermined period of time, to deposit a predetermined amount of fur in said layer; means for transporting said

layer of fur to a second location; means rendering operative said transporting means after halting of said removing and depositing means; means at said second location for agitating said layer of fur; means automatically rendering operative said agitating means for a predetermined period of time, commencing after halting of said transporting means; means automatically applying heat and moisture to said fur during the agitating thereof, to felt the fur into a substantially flat pad; means for transporting said felted pad to a third location; means automatically rendering said pad-transporting means operative upon completion of the felting of said fur; means at said third location for agitating said felted pad; means at said third location for applying heat and moisture to said pad; means at said third location for applying opposite pressures to outer and center portions respectively of said pad; and means automatically rendering operative said three immediately preceding means after transportation of the pad to said third location.

12. Apparatus for making hat bodies, comprising means for disposing fur in a substantially flat, uniform layer, said means including a fur-supply bin, a cooperable, hollow fur-collecting head having a perforated support, and means for producing reduced air pressure in said head to produce a suction at the support; means mounting said supply bin for movement between positions remote from and adjacent to said collecting head; means responsive to positioning of the supply bin adjacent the collecting head, rendering said suction-producing means operative for a predetermined period of time, to cause the deposit of a predetermined amount of fur on said support; means for felting said fur into a substantially flat pad; means automatically rendering operative said felting means for a predetermined period of time, commencing after halting of said fur-disposing means; means for applying opposing pressures to outer and center portions respectively of said pad; means for further felting said pad; and means automatically rendering operative the two immediately preceding means upon completion of felting of the fur into the flat pad.

13. Apparatus for making hat bodies, comprising a fur-supply bin having a discharge opening; a plurality of spaced fur-processing units, each having means, including a fur-collecting head adapted to cooperate with said bin, for removing fur from the bin through the discharge opening thereof and supporting the fur in a substantially flat, uniform layer; means mounting said supply bin for movement to and from a plurality of operative positions respectively adjacent said fur-processing units; and a plurality of means associated respectively with the processing units, each responsive to positioning of the supply bin in operative position adjacent the associated processing unit, automatically rendering operative the fur-removing and supporting means of said processing unit.

14. Apparatus for making hat bodies, comprising a fur-supply bin having a discharge opening; a plurality of spaced fur-processing units, each having means, including a fur-collecting head adapted to cooperate with said bin, for removing fur from the bin through the discharge opening thereof and supporting the fur in a substantially flat, uniform layer; means mounting said supply bin for movement to and from a plurality of operative positions respectively adjacent said fur-processing units; a plurality of means asso-

65

70

75

ciated respectively with the processing units, each responsive to positioning of the supply bin in operative position adjacent the associated processing unit, automatically rendering operative the fur-removing and supporting means of said processing unit; and means, automatically operative a predetermined time after any one of a plurality of said immediately preceding means becomes operative, moving said supply bin from one to another of said fur-processing units.

15. Apparatus for making hat bodies, comprising a fur-supply bin having a discharge opening; a shutter for closing said discharge opening; a plurality of spaced fur-processing units, each having means, including a fur-collecting head adapted to cooperate with said bin, for removing fur from the bin through the discharge opening thereof and supporting the fur in a substantially flat, uniform layer; means mounting said supply bin for movement to and from a plurality of operative positions respectively adjacent said fur-processing units; a plurality of means associated respectively with the processing units, each responsive to positioning of the supply bin in operative position adjacent the associated processing unit, automatically rendering operative the fur-removing and supporting means of said processing unit; and means automatically closing said shutter a predetermined time after any one of said immediately preceding means becomes operative.

16. Apparatus for making hat bodies, comprising a fur-supply bin having a discharge opening; a shutter for closing said discharge opening; a plurality of spaced fur-processing units, each having means, including a fur-collecting head adapted to cooperate with said bin, for removing fur from the bin through the discharge opening thereof and supporting the fur in a substantially flat, uniform layer; means mounting said supply bin for movement to and from a plurality of operative positions respectively adjacent said fur-processing units; a plurality of means associated respectively with the processing units, each responsive to positioning of the supply bin in operative position adjacent the associated processing unit, automatically rendering operative the fur-removing and supporting means of said processing unit; means automatically closing said shutter a predetermined time after any one of a plurality of said immediately preceding means becomes operative; and means automatically operative a predetermined time after each closing of said shutter, moving said supply bin from one to another of said fur-processing units.

17. Apparatus for making hat bodies, comprising a fur-supply bin having a top discharge opening; a pair of shutters one above the other, each arranged to individually close said discharge opening; a plurality of spaced fur-processing units, each having means, including a fur-collecting head adapted to cooperate with said bin, for removing fur from the bin through the discharge opening thereof and supporting the fur in a substantially flat, uniform layer; means mounting said supply bin for movement to and from a plurality of operative positions respectively adjacent said fur-processing units; a plurality of means associated respectively with the processing units, each responsive to positioning of the supply bin in operative position adjacent the associated processing unit, automatically rendering operative the fur-removing and supporting means of said processing unit; means automatically closing the lower shutter a predetermined time after any one of a plurality of said immediately preceding

means becomes operative; means, automatically operative a predetermined time after each closing of said lower shutter, moving said supply bin from one to another of said fur-processing units; means, automatically operative a predetermined time after each closing of said lower shutter, closing the upper shutter; and means automatically operative a predetermined time after closing of the upper shutter, opening the said lower shutter.

18. Apparatus for making hat bodies, comprising a fur-supply bin having a top discharge opening; a pair of shutters one above the other, each arranged to individually close said discharge opening; a plurality of spaced fur-processing units, each having means, including a fur-collecting head adapted to cooperate with said bin, for removing fur from the bin through the discharge opening thereof and supporting the fur in a substantially flat, uniform layer; means mounting said supply bin for movement to and from a plurality of operative positions respectively adjacent said fur-processing units; a plurality of means associated respectively with the processing units, each respective to positioning of the supply bin in operative position adjacent the associated processing unit, automatically rendering operative the fur-removing and supporting means of said processing unit; means automatically closing the lower shutter a predetermined time after any one of a plurality of said immediately preceding means becomes operative; means, automatically operative a predetermined time after each closing of said lower shutter, moving said supply bin from one to another of said fur-processing units; means, automatically operative a predetermined time after each closing of said lower shutter, closing the upper shutter; and means responsive to closing of the upper shutter, opening the said lower shutter.

19. The invention as defined in claim 10 in which the fur-supply bin has a discharge opening in its top and a shutter mechanism for closing said opening, and in which the means for disposing fur includes means moving and maintaining the fur-collecting head against the discharge opening of the bin, and includes means actuating the shutter mechanism to open the discharge opening during the time the head is against said opening.

20. Apparatus for making hat bodies, comprising a fur-supply bin, a felting stand and a forming stand equispaced in a row; a substantially flat support, a hat mold and a recessed supporting member; means fastening together said support, mold and member in line with each other and with a spacing equivalent to that of the supply bin, felting stand and forming stand; means mounting said fastening means for movement between a position wherein the support, mold and member are respectively at the supply bin, felting stand and forming stand, and a position wherein the support and mold are at the felting stand and forming stand respectively; means for transferring a predetermined amount of fur from the supply bin to the support when the latter is at the bin; means for maintaining said fur on the support during movement of the support from the supply bin to the felting stand; means at the felting stand for felting the fur on the support into a substantially flat pad; means for transferring said pad from the felting stand to the hat mold when the mold is at said stand; means for forming a crown in said transferred pad when the mold and pad are at the forming stand; means for transferring said formed pad to the recessed

supporting member when the latter is at the forming stand; and means providing for discharge of said formed pad from the recessed member when the latter is removed from the forming stand.

21. Apparatus for making hat bodies, comprising a fur-supply bin, a felting stand and a forming stand equispaced in a row; means mounting the bin for movement from and to its position in said row; a substantially flat support, a hat mold and a recessed supporting member; means fastening together said support, mold and member in line with each other and with a spacing equivalent to that of the supply bin, felting stand and forming stand; means mounting said fastening means for movement between a position wherein the support, mold and member are respectively at the supply bin, felting stand and forming stand, and a position wherein the support and mold are at the felting stand and forming stand respectively; cyclic means for moving said support, mold and recessed member through a cycle wherein they sequentially occupy the preceding positions; means for transferring a predetermined amount of fur from the supply bin to the support when the latter is at the bin; means for maintaining said fur on the support during movement of the support from the supply bin to the felting stand; means at the felting stand for felting the fur on the support into a substantially flat pad; means for transferring said pad from the felting stand to the hat mold when the mold is at said stand; means for forming a crown in said transferred pad when the mold and pad are at the forming stand; means for transferring said formed pad to the recessed supporting member when the latter is removed from the forming stand; and means responsive to positioning of the bin in said row, for activating said cyclic means.

22. Apparatus for making hat bodies, comprising a fur-supply bin, a felting stand and a forming stand equispaced in a row; means mounting the bin for movement from and to its position in said row; a substantially flat support, a hat mold and a recessed supporting member; means fastening together said support, mold and member in line with each other and with a spacing equivalent to that of the supply bin, felting stand and forming stand; means mounting said fastening means for movement between a position wherein the support, mold and member are respectively at the supply bin, felting stand and forming stand, and a position wherein the support and mold are at the felting stand and forming stand respectively; cyclic means for moving said support, mold and recessed member through a cycle wherein they sequentially occupy the preceding positions; means for transferring a predetermined amount of fur from the supply bin to the support when the latter is at the bin; means for maintaining said fur on the support during movement of the support from the supply bin to the felting stand; means for felting the fur on the support into a substantially flat pad at the felting stand; means for transferring said pad from the felting stand to the hat mold when the mold is at said stand; means for forming a crown in said transferred pad when the mold and pad are at the forming stand; means for transferring said formed pad to the recessed supporting member when the latter is at the forming stand;

means providing for discharge of said formed pad from the recessed member when the latter is removed from the forming stand; means responsive to positioning of the bin in said row, for activating said cyclic means; and automatic means for moving said bin away from its position in said row a predetermined time after activation of said cyclic means.

23. Apparatus for making hat bodies, comprising a fur-supply bin, a felting stand and a forming stand equispaced in a row; means mounting the bin for movement from and to its position in said row, said bin having a discharge opening in its top; a shutter mechanism for closing said opening; a substantially flat support, a hat mold and a recessed supporting member; means fastening together said support, mold and member in line with each other and with a spacing equivalent to that of the supply bin, felting stand and forming stand; means mounting said fastening means for movement between a position wherein the support, mold and member are respectively at the supply bin, felting stand and forming stand, and a position wherein the support and mold are at the felting stand and forming stand respectively; cyclic means for moving said support, mold and recessed member through a cycle wherein they sequentially occupy the preceding positions; means for transferring a predetermined amount of fur from the supply bin to the support when the latter is at the bin, including means actuating the bin shutter mechanism to maintain the discharge opening of the bin open for a predetermined interval; means for maintaining said fur on the support during movement of the support from the supply bin to the felting stand; means for felting the fur on the support into a substantially flat pad at the felting stand; means for transferring said pad from the felting stand to the hat mold when the mold is at said stand; means for forming a crown in said transferred pad when the mold and pad are at the forming stand; means for transferring said formed pad to the recessed supporting member when the latter is at the forming stand; means providing for discharge of said formed pad from the recessed member when the latter is removed from the forming stand; and means responsive to positioning of the bin in said row, for activating said cyclic means.

24. Apparatus for making hat bodies, comprising a fur-supply bin, a felting stand and a forming stand equispaced in a row; means mounting the bin for movement from and to its position in said row; a substantially flat support, a hat mold and a recessed supporting member; means fastening together said support, mold and member in line with each other and with a spacing equivalent to that of the supply bin, felting stand and forming stand; means mounting said fastening means for movement between a position wherein the support, mold and member are respectively at the supply bin, felting stand and forming stand, and a position wherein the support and mold are at the felting stand and forming stand respectively; cyclic means for moving said support, mold and recessed member through a cycle wherein they sequentially occupy the preceding positions for predetermined intervals of time; means automatically transferring a predetermined amount of fur from the supply bin to the support whenever the latter is brought to and maintained at the bin; means automatically maintaining fur on the support during movements of the support from the supply bin to the

75 felting stand; means automatically felting fur on the support into a substantially flat pad whenever the support is brought to and maintained at the felting stand; means automatically transferring a pad from the felting stand to the hat mold whenever the mold is brought to and maintained at said stand; means automatically forming a crown in a transferred pad whenever the mold and pad are brought to and maintained at the forming stand; means automatically transferring a formed pad to the recessed supporting member whenever the latter is brought to and maintained at the forming stand; and means providing for discharge of a formed pad from the recessed member whenever the latter is removed from the forming stand.

20 25. Means for forming a flat, loosely felted pad into a crown shape, comprising a perforated member having the shape of a hat body, including crown and brim portions; a perforated flat member having a large opening in its center portion; means mounting the members for relative movement to enable them to be separated or brought together with the flat member broadside to the brim portion of the other member to hold a felted pad between them; a crown-shaped perforated member; means mounting the crown-shaped member for movement through the opening of the flat member and into the crown portion of the first-named member when the latter and the flat member are together; and means for directing hot liquid against at least one of said perforated members, to cause a further felting of the pad.

30 35 40 45 50 55 26. Means for forming a flat, loosely felted pad into a crown shape, comprising a perforated member having the shape of a hat body, including crown and brim portions; a perforated flat member having a large opening in its center portion; means mounting the members for relative movement to enable them to be separated or brought together with the flat member broadside to the brim portion of the other member to hold a felted pad between them; means for oscillating the flat member edgewise; a crown-shaped perforated member; means mounting the crown-shaped member for movement through the opening of the flat member and into the crown portion of the first-named member when the latter and the flat member are together; power means for advancing said crown-shaped member throughout its path of movement; and means for directing hot liquid against at least one of said perforated members, to cause a further felting of the pad.

60 65 70 75 27. Means for forming a flat, loosely felted pad into a crown shape, comprising a perforated member having the shape of a hat body, including crown and brim portions; a perforated flat member having a large opening in its center portion; means mounting the members for relative movement to enable them to be separated or brought together with the flat member broadside to the brim portion of the other member to hold a felted pad between them; means for oscillating the flat member edgewise; a crown-shaped perforated member; means mounting the crown-shaped member for movement through the opening of the flat member and into the crown portion of the first-named member when the latter and the flat member are together; power means for intermittently advancing said crown-shaped member throughout its path of movement; and means for directing hot liquid against at least

one of said perforated members, to cause a further felting of the pad.

28. The invention as defined in claim 27 in which the power means enables the crown-shaped member to have retrograde movements of lesser magnitude than the advancing movements, and in which the hot liquid is directed against the flat member and crown-shaped member.

GEORGE T. BIRDSALL. 10
